TOBACCO BARN STRUCTURE

Gilder S. Horne, Charlotte, N. C.

Application April 25, 1949, Serial No. 89,439

8 Claims. (Cl. 98—52)

1

This invention relates to improvements in tobacco barns employed in the curing of tobacco and more especially to an improved ventilating apparatus adapted to be mounted at the apex of hip roof types of tobacco barns and which is operable from the ground floor of the barn and whereby the amount of air passing upwardly through the tobacco being dried may be regulated.

In a tobacco barn there is provided a plurality of superposed tier poles on which the tobacco is hung for a curing operation. In one form of harvesting tobacco, the stalks are split from the top down to a distance short of the bottom and then the tobacco stalk is cut below the point where the lowermost leaves on the stalk are located, and the split stalk of tobacco is thrown astride a stick, the stalks of tobacco hanging in an inverted position and these sticks are hung on the tier poles in the tobacco barn. In more recent years, the preferred manner of harvesting tobacco is to strip the lowermost leaves from the stalk, since the leaves begin ripening at the bottom, and progressively ripen toward the top of the stalk, and pack these leaves in suitable containers, which are usually wheeled or on sleds, and are drawn between the rows of tobacco. These containers full of leaves are then drawn to the barn or to a point adjacent the barn where they are strung on suitable tobacco sticks, leaving a naked portion at each end of the stick of several inches length.

Then these sticks of tobacco are passed upwardly by one person standing on two tier poles and handing a stick up to another person thereabove on two other tier poles, and so on until the sticks are placed on the topmost tier poles and the tobacco barn is thus filled with tobacco sticks with tobacco thereon, from the top to the bottom. These sticks with the leaves thereon are packed rather closely together and in the beginning of a curing operation, it is necessary to have a good bit of ventilation from the bottom to the top of the tobacco barn, since heat is generally generated at the bottom of the tobacco barn and rises upwardly as any hot air will rise, and sometimes it is necessary to create an upward draft through the leaves, especially in the primary stages of curing so as to cause the heat generated on the ground floor to pass upwardly through all of the tobacco leaves to dry the same. At other times, in further advanced stages of curing, it is also necessary to vent some hot air at the top of the barn to prevent the topmost portion of the barn from becoming overheated.

2

In any event, suitable ventilating means at the top of the barn are necessary and various attempts have heretofore been made to secure such ventilation, but have not proved entirely satisfactory. It is therefore an object of this invention to provide an improved ventilating means for tobacco barns having hip roofs or pyramidal type roofs and which may be readily adapted to this type of roof with a minimum of additional framing and which may be operable from the ground floor of the barn for regulating the size of the opening to control the rate at which the air is vented from the center of the roof and to further provide other means cooperating therewith to minimize turbulence at the ventilating means, thus insuring a uniform discharge of air from within the tobacco barn regardless of the direction or velocity of the wind.

In a tobacco barn it is preferable to have suitable openings near the bottom thereof to admit air into the barn which rises upwardly through the leaves of tobacco in the barn and outwardly through the ventilating means in the top of the barn.

It is another object of this invention to provide in combination with a tobacco barn having a hip roof or pyramidal roof, said barn being provided with a rectangular opening at the juncture of the hip rafters, substantially triangular doors hinged to the side edges of the opening and pivoted arms extending from the center of each of the hinged doors to a common vertically extending pole or staff to which they are pivotally connected, there being guiding means for the vertically extending pole and means on the pole for locking the pole in any desired position relative to the vertical upon the pole being raised or lowered by an operator for opening or closing the hinged doors.

It is another object of this invention to provide a ventilating apparatus for tobacco barns having a pyramidal roof and the roof being provided with a square opening at its apex, comprising triangular doors hinged to the side edges of said opening, each of the triangular doors having a bar secured to its lower surface and extending a substantial distance beyond the edge of the said opening in a direction remote from the free end of the door. The upper ends of cables are connected to the lower ends of the bars on the doors and converge downwardly and are connected to one end of a lever arm pivoted at its other end on one of the rafters and having a cable depending from the lever arm intermediate its ends, to thus provide means whereby the hinged doors

may be opened by an operator pulling the cable downwardly. This cable may be disposed off-center relative to the opening in the roof so as to be disposed closely adjacent the tier poles and to thereby avoid interference with placing the tobacco sticks on the tier poles.

In another form of the invention I have provided lever arms pivotally connected to the bottoms of the hinged doors, the lower ends of which are hingedly connected to a common vertically movable post of relatively short length, and from the upper end of which a guide pin projects and extends through the usual center post to which the hip rafters are secured at their upper ends. A lever arm is pivotally connected to the vertically movable post at one end thereof and the other end of the lever arm has a cord, cable or the like, extending downwardly therefrom in offset relation to the center of the roof to thus pass immediately adjacent tier poles. This lever arm is oscillatably mounted intermediate its ends on the framework of the barn to thus cause the doors to be opened equal distances with respect to each other when the cable is pulled downwardly by an operator, it being understood that the operator may tie the lower end of the cable around one of the lowermost tier poles adjacent the same when the doors have been opened a desired amount.

Some of the objects of the invention having been stated, other objects will appear as the description proceeds, when taken in connection with the accompanying drawings, in which—

Figure 1 is an isometric view of a typical hip roof tobacco barn showing the improved ventilating apparatus mounted on the roof thereof;

Figure 2 is a vertical sectional view through the barn and is taken substantially along the line 2—2 in Figure 1;

Figure 3 is an enlarged sectional plan view showing one of the guiding means and the supporting means for the vertically movable staff;

Figure 4 is a view similar to Figure 3 and is taken substantially along the line 4—4 in Figure 2;

Figure 5 is an enlarged top plan view with parts in section and is taken substantially along the line 5—5 in Figure 2 and showing the manner in which the hinged doors are mounted at the apex of the hip roof;

Figure 6 is a plan view showing a layout of a preferred form of roof framing to be employed in conjunction with the present invention;

Figure 7 is a vertical sectional view taken substantially along the line 7—7 in Figure 5 and showing the hinged doors in closed position;

Figure 8 is a view similar to Figure 7 but showing the hinged doors in open position;

Figure 9 is a vertical sectional view similar to Figure 7 but showing a modified means for controlling the position of the doors;

Figure 10 is a view similar to Figure 9 but showing the hinged doors in open position;

Figure 11 is another view similar to Figure 7 showing the doors in closed position but showing still another modified means for opening and closing the doors;

Figure 12 is a view similar to Figure 11 but showing the hinged doors in open position;

Figure 13 is an enlarged top plan view showing the center post in cross section and taken substantially along the line 13—13 in Figure 11.

Referring more specifically to the drawings, the numeral 10 broadly designates a tobacco barn which may be of any desired construction, but it

is preferable that the barn 10 be constructed in the manner shown in the drawings and in the manner to be presently described.

The foundation for the tobacco barn comprises a plurality of concrete blocks, 11, alternate ones of which are turned on their sides to thus expose their air spaces 12 and to allow air to pass therethrough.

Disposed on top of the blocks 11 are the sills 13 and secured on the top of these sills 13 are a plurality of spaced uprising studs or frame members 14, on the top ends of which the usual plate members 15 are secured.

The lower ends of hip rafters 20 to 23, inclusive, are secured to the plate members 15 at the corners of the barn 10 and extend upwardly and inwardly and their proximate ends are suitably secured to a vertically disposed center block 24. A plurality of jack rafters 25 are secured at their upper ends to the sides of the hip rafters 20 to 23, inclusive, and their lower ends are suitably secured to the plates 15 (Figures 2 and 6).

The barn is provided with a plurality of tier poles 30 secured at their ends to the upright studs 14 and on which tobacco sticks, not shown, with tobacco thereon, are adapted to be placed for a curing operation.

A preferred wall structure for tobacco barns of this type comprises a layer of matched boards 31 secured to the outer edges of the stud members 14 and to which panels of mineral surfaced insulation board 32 are secured, to thus provide an insulated wall for the barn 10. The rafters 20, 21, 22, 23 and 25 are also covered in the same manner as the walls of the building 10 and have suitable matched boards 34 secured on the top edges thereof, to which a suitable mineral surfaced insulation board 35 is secured, to thus provide an insulation covering for the pyramidal roof 39 of the barn 10. Before the roofing boards 34 are secured to the rafters, suitable spacing blocks 36 (Figure 2) are secured to the plate members 15 and span the distance between adjacent rafters, thus completing the general structure of the barn 10.

The matched boards 34 and the insulation material 35 at the roof of the barn 10 are cut away to form an opening 40 at the junction point of the hip rafters 20 to 23, inclusive. It will be noted that the hip rafters 20 to 23, inclusive, are not cut away beneath the area defined by the opening 40.

Secured to the top edges of the hip rafters 20 to 23, inclusive, are vertically disposed corner posts 41 to 44, inclusive, respectively (Figure 5), which extend upwardly a substantial distance above the apex of the roof and have suitable horizontally disposed frame members 46 secured thereto, to the upper surfaces of which a horizontally disposed plate member 47, which may be of any desired material such as wood, metal, plastic, or the like, is suitably secured. Spaced below the upper ends of the corner posts 41 to 44, inclusive and being secured thereto, are horizontally disposed frame members 50 to which the upper ends of side panels 52, 53, 54 and 55 are suitably secured, the lower ends of the panels 52 to 55, inclusive, being secured to suitable frame members 56 fastened to the corner posts 41 to 44, inclusive, at the juncture of the corner posts and the insulation roofing material 35. The members 41 to 55, inclusive, form a hollow member having vertical wall members.

Hingedly connected, as by strap hinges 60, to the roofing boards 34, are hinged doors 61 to 64,

inclusive. These hinged doors are frustro-triangular in shape and are adapted to cover the opening 40 defined by the roofing materials 34 and 35. The hinged doors 61 normally rest on and span the distance between the upper portions of the hip rafters 22 and 20. The door 62 spans the distance between and is adapted to normally rest on the hip rafters 20 and 21. The hinged door 63 spans the distance between and is adapted to normally rest on the hip rafters 21 and 23. The hinged door 64 spans the distance between and normally rests on the hip rafters 22 and 23.

It will be noted that the lower outermost corners of all of the hinged doors 61 to 64, inclusive, are cut away to thus clear the corner posts 41 to 44, inclusive, as they are raised and lowered by means to be presently described.

Referring to Figures 2, 5, 7 and 8, it may be observed that there is, suitably secured to the lower surface of the hinged doors 61 to 64, inclusive, a cleat 67 to which the upper ends of links 71 to 74 inclusive, respectively, are pivotally connected as at 75. The lower ends of the links 71 and 73 are oscillatably mounted adjacent opposite ends of a pin 75 which slidably penetrates a suitable staff 76 near the upper end thereof. This pin 75 is threaded at opposite ends thereof for reception of suitable nuts 77 to thus confine the lower ends of the links 71 and 73 on the rod 75 and against opposite sides of the staff 76.

The lower ends of the links 72 and 74 are mounted in an identical manner to the lower ends of the links 71 and 73, the pin being indicated at 80. The staff 76 depends from the links 71 to 74, inclusive, and is mounted for vertical sliding movement against a transverse bar 82 disposed between the centrally located tier poles 30 and in the lowermost row of the same. The staff 76 also has vertical sliding movement against a similar transverse bar 83 disposed between a pair of centrally located intermediate tier poles 30 and each of the transverse bars 83 and 82 (Figure 2) has a pair of spaced blocks 84 and 85 capped by a bar 86 secured thereto by any suitable means such as nails 87 (Figures 3 and 4).

The blocks 84 and 85 and the associated cap member 86 serve as guide members for vertical movement of the staff 76 and it will be noted in Figure 3 that the lower portion of the staff 76 is provided with a plurality of holes or bores 90, any one of which is adapted to slidably receive a lock pin 91 which is adapted to engage the upper surface of the bar 82 and the associated bar 86 (Figure 3) to support the weight of the staff 76 and the hinged doors 61 to 64, inclusive, when they are in an opened position as shown in Figure 8.

It is thus seen that by raising the staff 76 from the lowered position shown in Figures 2 and 7 to, say, the position shown in Figure 8, the link members 71 to 74, inclusive, will cause the hinged doors 61 to 64, inclusive, respectively, to be moved upwardly at their proximate upper edges and the pin 91 (Figure 3) may be inserted in any one of the bores 90 in the lower portion of the staff 76 to thus hold the doors 61 to 64, inclusive, in open position and to thus regulate the size of the opening 40 at the apex of the roof of the tobacco barn 10.

The purpose of the walls 52 to 55, inclusive, is to provide the effect of a stack or chimney, the upper edges of these walls terminating high

5 enough above any sloping roof sections to minimize air turbulence and to avoid down drafts. The plate member 47 primarily serves to prevent rain and the like from falling through the opening when the doors 61 to 64 are in an open position. The plate 47 is made as thin as possible so as to not interfere with the normal currents of air passing above and below the same, particularly in the case of winds of a relatively high 10 velocity.

First modified form of the invention

Referring to Figures 9 and 10, there may be observed a modified means for opening the hinged doors 61 to 64, inclusive. Since the roof structure and the manner in which the doors are mounted in Figures 9 and 10 is identical to the manner in which they are mounted in Figures 1, 2, 5, 6, 7 and 8, like parts shall bear the same reference characters and only the modifications will be hereinafter described.

Each of the doors 61 to 64, inclusive, has suitably secured to the lower surface thereof a bar 95. Each of the bars 95 projects a substantial distance beyond the hinged edge of the corresponding door and the bars 95 associated with the doors 62 and 64 have opposite ends of a cable or cord 96 connected thereto, there being a cable 97 extending from the hinged doors 61 and 63 in the same manner that the cable 95 is connected to the bars 95 associated with the doors 62 and 64.

The cables 96 and 97 may be tied together in any suitable manner at their juncture, however, in this instance there is a suitable ring 100 through which the cables 96 and 97 are adapted to pass. This ring 100 has a link 101 depending therefrom, the lower end of which is connected to the free end of a lever arm 103. The other end of this lever arm 103 may be connected to the framework of the roof in any desired manner and, in this instance, the lever arm 103 is shown as being pivotally connected as at 104 to one of the jack rafters 25. In Figures 9 and 10 the upper end of a control cable 105 is connected to the lever arm 103 adjacent its pivoted point 104 and it is thus seen that the cable 105 is disposed to one side of the center of the building and may thus extend downwardly past and closely adjacent the tier poles 30 as arranged in Figure 2 and thus will leave the space between the tier poles clear of obstructions which would interfere with placing the conventional tobacco sticks on the tier poles.

Second modified form

Referring to Figures 11, 12 and 13 there is shown a second modified means for controlling the opening and closing of the hinged doors 61 to 64, inclusive. As in the first modified form, the roof structure and the manner in which the hinged doors are mounted is identical to that shown in the original form of the invention shown in Figures 1, 2, 5, 6, 7 and 8 and, therefore, like parts shall again bear the same reference characters and only the modifications will hereinafter be described.

In the second modified form of the invention, shown in Figures 11, 12 and 13, the hinged doors 61 to 64, inclusive, also have the cleat 67 suitably secured to the lower surface thereof, as in the original form of the invention. Pivotally connected, as at 110, to each of the cleats 67 is an angularly disposed link 111 which extends downwardly and inwardly and is hingedly secured as

at 112 adjacent the upper end of a vertically disposed common post 114.

The lower end of a vertically disposed guide rod 115 is threadably imbedded in the upper end of the common post 114 and slidably penetrates the center of the block 24 heretofore described. This pin 115 is preferably headed as at 116 at its upper end, this head portion 116 being adapted to engage the upper surface of the block 24 when the doors 61 to 64, inclusive, are in a closed position as shown in Figure 11.

In this second modified form of the invention it is preferable to provide horizontally disposed header frame members 120 between the proximate sides of adjacent jack rafters 25, there being one of these headers 120 at each of two opposed downwardly sloping portions of the pyramidal roof. Extending between these header frame members 120 is a horizontally disposed tie frame member 121 which is preferably offset slightly with respect to the common post 114 to thus permit the common post 114 to pass freely thereby.

A suitable spacing block 123 (Figure 13) is secured, as by nailing, to one of the vertical sides of the cross frame member 121 and is slidably penetrated by a bolt 124 on which a lever arm 125 is oscillatably mounted intermediate its ends.

The left-hand end of this lever arm 125 in Figures 11 and 12 is provided with a longitudinally extending slot 126 which is slidably penetrated by a bolt 127 which also slidably penetrates the lower portion of the common post 114.

The free right-hand end of the lever arm 125 has the upper end of a cable, cord or the like 130, connected thereto which depends from the arm 125 and extends downwardly to near the floor of the barn and within reach of an operator. It is thus seen that the cable 130 is disposed off center to one side of the vertical center of the barn 10 and thus this cable 130 may be disposed closely adjacent or between adjacent tier poles 17 which are shown in Figure 2. By grasping the cable 130 and pulling the same downwardly, an operator may move the lever 125 in a clockwise direction in Figure 11 to the position shown in Figure 12, to fully open the hinged doors 61 to 64, inclusive, or, if desired, the doors 61 to 64 may be opened or swung upwardly to any desired position, and then the lower end of the cable 130 may be secured to one of the tier poles 30. It is manifest that it would merely be necessary to release the cable 130 and the doors 61 to 64 would close, by gravity, since their combined weight is substantially greater than the weight of the right-hand portion of the lever arm 125 and the cable 130 depending therefrom.

The use of a ventilating apparatus of this type with a pyramidal roof, obviously, insures an even flow of air from all parts of the barn when the doors 61 to 64 are in an open position.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a tobacco barn having a foundation, and also having side walls supported on the foundation, and also having a pyramidal-shaped roof supported on the upper ends of the side walls, said roof being provided with a rectangular opening at its apex, an open-ended hollow member having vertically disposed wall members secured

to said roof, one wall member being adjacent each side of said rectangular opening, a horizontally disposed plate member mounted in spaced relation to the upper ends of said vertically disposed wall members, a substantially triangular door hingedly connected to the roof at each of the sides of the rectangular opening, said roof being provided with hip rafters extending inwardly and upwardly from each corner thereof and being joined together at their upper proximate ends and said hip rafters spanning said opening, the said hinged doors normally resting on the hip rafters, a vertically movable staff extending from adjacent the bottom floor of the barn and terminating a substantial distance below the apex of the pyramidal roof, link members pivotally connected to the upper end of said staff and being connected at their other ends to the bottoms of the said hinged doors whereby, upon moving the said staff upwardly, the doors will be moved apart from each other at their proximate upper edges to thus regulate the size of the opening between the free ends of said hinged doors and means on said staff for locking the staff in a desired elevated position for holding the hinged doors at a predetermined angular position.

2. In a tobacco barn having a foundation, and also having side walls supported on the foundation, and also having a pyramidal-shaped roof supported on the upper ends of the side walls, said roof being provided with a rectangular opening at its apex, a substantially triangular door hingedly connected at the base thereof to the roof at each of the sides of the rectangular opening, said roof being provided with hip rafters extending inwardly and upwardly from each corner thereof and being joined together at their upper proximate ends and said hip rafters spanning said opening, the said hinged doors normally resting on the hip rafters, a vertically movable staff extending from adjacent the bottom floor of the barn and terminating a substantial distance below the apex of the pyramidal roof, link members pivotally connected to the upper end of said staff and being connected at their other ends to the bottoms of the said hinged doors whereby, upon moving the said staff upwardly, the doors will be moved apart from each other at their proximate upper edges to thus regulate the size of the opening between the free ends of said hinged doors and means on said staff for locking the staff in a desired elevated position for holding the hinged doors at a predetermined angular position, a rectangular framework supported by said hip rafters and extending upwardly a substantial distance above said opening, a horizontally disposed cover plate secured to the upper end of the rectangular framework, side wall members secured to the framework, the upper ends of said side wall members being spaced a substantial distance below said cover member to thus induce an even flow of air under windy conditions across and above said opening and whereby upon moving said hinged doors upwardly, a uniform passage of air upwardly through the opening may be insured.

3. In a tobacco barn having a pyramidal-shaped roof, said roof being provided with a rectangular opening at its center, an open-ended hollow member having vertically disposed wall members secured to said roof, one wall member being adjacent each side of said rectangular opening, a horizontally disposed plate member mounted in spaced relation to the upper ends of said vertically disposed wall members, a substantially triangular door hingedly connected to the roof at

each of the sides of the rectangular opening, said roof being provided with hip rafters extending from the lower edges of said roof and across the said opening and terminating at the center of said opening, and a block of substantially the length of the ends of the rafters and to which the ends of the rafters are adapted to be secured, the hinged doors normally resting on the hip rafters, a relatively short vertically disposed common post disposed below the said block, link members pivotally connected to the common post and extending from said common post to each of the hinged doors and being pivotally connected at their other ends to the bottoms of said hinged doors, a lever arm pivotally connected to the common post at one end thereof and being oscillatably mounted intermediate its ends adjacent the common post, a cable depending from the free end of said lever arm and terminating adjacent the bottom floor of the tobacco barn, whereby an operator may pull said cable downwardly for raising the doors to a desired elevation at their proximate upper ends to permit air to be discharged through the opening from the interior of the barn, and a guide rod connected to the upper end of said common post and being slidably mounted in the said block to thus insure vertical movement of the common post in a straight line upon movement being imparted thereto by the said cable being pulled downwardly by an operator.

4. In a tobacco barn having a foundation and also having side walls supported on the foundation and also having a pyramidal-shaped roof supported on the upper ends of the side walls, said roof being provided with a rectangular opening at its center, an open-ended hollow member having vertically disposed wall members secured to said roof, one wall member being adjacent each side of said rectangular opening, a horizontally disposed plate member mounted in spaced relation to the upper ends of said vertically disposed wall members, doors hingedly connected to the roof at the sides of the rectangular opening, said roof being provided with hip rafters extending inwardly and upwardly from each corner thereof and being joined together at their upper ends and said rafters spanning said opening, the said hinged doors being adapted to normally rest on the hip rafters, a bar secured to the lower surface of each of the hinged doors and extending a substantial distance beyond the hinged end of the same, converging cables extending from the free ends of said bars, a lever arm connected at its free end to the cables at a point substantially in vertical alinement with the center of the opening, means pivotally connecting said lever arm at its other end to the rafters, a cable connected at its upper end to the lever intermediate its ends and depending therefrom, said cable being positioned to one side of the vertical center of the opening whereby, upon an operator grasping and pulling said cable downwardly, the free end of the lever arm will also move downwardly in an arcuate path to thus pull the cables downwardly at their juncture and thus moving the free upper edges of the doors apart from each other for permitting egress of air from within the barn.

5. In a tobacco barn having a pyramidal-shaped roof, said roof being provided with a rectangular opening at its center, an open-ended hollow member having vertically disposed wall members secured to said roof, one wall member being adjacent each side of said rectangular opening, a horizontally disposed plate member mount-

ed in spaced relation to the upper ends of said vertically disposed wall members, a substantially triangular door hingedly connected to the roof at each of the sides of the rectangular opening, said roof being provided with hip rafters extending from the lower edges of said roof and across the said opening and terminating at the center of said opening, and a block of substantially the length of the ends of the rafters and to which the ends of the rafters are adapted to be secured, the hinged doors normally resting on the hip rafters, a relatively short vertically movable common post disposed below the said block, a guide rod connected to said common post and being slidably mounted in said block, link members pivotally connected to the common post and extending from said common post to each of the hinged doors and being pivotally connected at their other ends to the bottoms of said hinged doors, said barn also having a frame member disposed below said opening, a lever arm pivotally connected to the common post at one end thereof and being oscillatably mounted intermediate its ends on said frame member, a cable depending from the free end of said lever arm and terminating adjacent the bottom floor of the tobacco barn, whereby an operator may pull said cable downwardly for raising the doors to a desired elevation at their proximate upper ends to permit air to be discharged through the opening from the interior of the barn, the walls of the barn having a plurality of openings in the lower portions thereof through which air may be admitted to the barn to pass upwardly and outwardly through said opening.

6. In a tobacco barn having a pyramidal-shaped roof, said roof being provided with a rectangular opening at its center, a substantially triangular door hingedly connected to the roof at each of the sides of the rectangular opening, said roof being provided with hip rafters extending from the lower edges of said roof and across the said opening and terminating at the center of said opening, and a block of substantially the length of the ends of the rafters and to which the ends of the rafters are adapted to be secured, the hinged doors normally resting on the hip rafters, a relatively short vertically movable common post disposed below the said block, a guide rod connected to said common post and being slidably mounted in said block, link members pivotally connected to the common post and extending from said common post to each of the hinged doors and being pivotally connected at their other ends to the bottoms of said hinged doors, said barn also having a frame member disposed below said opening, a lever arm pivotally connected to the common post at one end thereof and being oscillatably mounted intermediate its ends on said frame member, a cable depending from the free end of said lever arm and terminating adjacent the bottom floor of the tobacco barn, whereby an operator may pull said cable downwardly for raising the doors to a desired elevation at their proximate upper ends to permit air to be discharged through the opening from the interior of the barn, a rectangular framework supported by said hip rafters and extending upwardly a substantial distance above said opening, a horizontally disposed cover plate secured to the upper end of the rectangular framework, side wall members secured to the framework, the upper ends of said side wall members being spaced a substantial distance below said cover member to thus induce an even flow of air under windy conditions across and above said

11

opening and whereby upon moving said hinged doors upwardly, a uniform passage of air upwardly through the opening may be insured.

7. In a tobacco barn having a foundation and also having side walls supported on the foundation and also having a pyramidal-shaped roof supported on the upper ends of the side walls, said roof being provided with a rectangular opening at its center, doors hingedly connected to the roof at the sides of the rectangular opening, said roof being provided with hip rafters extending inwardly and upwardly from each corner thereof and being jointed together at their upper ends and said rafters spanning said opening, the said hinged doors being adapted to normally rest on the hip rafters, a bar secured to the lower surface of each of the hinged doors and extending a substantial distance beyond the hinged end of the same, converging cables extending from the free ends of said bars, a lever arm connected at its free end to the cables at a point substantially in vertical alinement with the center of the opening, means pivotally connecting said lever arm at its other end to the rafters, a cable connected at its upper end to the lever intermediate its ends and depending therefrom, said cable being positioned to one side of the vertical center of the opening whereby, upon an operator grasping and pulling said cable downwardly, the free end of the lever arm will also move downwardly in an arcuate path to thus pull the cables downwardly at their juncture and thus moving the free upper edges of the doors apart from each other for permitting egress of air from within the barn, a rectangular framework supported by said hip rafters and extending upwardly a substantial distance above said opening, a horizontally disposed cover plate secured to the upper end of the rectangular framework, side wall members secured to the framework, the upper ends of said side wall members being spaced a substantial distance below said cover member to thus induce an even flow of

12

air under windy conditions across and above said opening and whereby upon moving said hinged doors upwardly a uniform passage of air upwardly through the opening may be insured.

8. In a tobacco barn having a foundation and also having side walls supported on the foundation and also having a pyramidal-shaped roof supported on the upper ends of the side walls, said roof being provided with a rectangular opening at its apex, an open-ended hollow member having vertically disposed wall members secured to the upper surface of said roof and surrounding said rectangular opening, a horizontally disposed plate member mounted in spaced relation to the upper end of the hollow member, a substantially triangular door hingedly connected to the roof at each of the sides of the rectangular opening, said roof being provided with hip rafters extending inwardly and upwardly from each corner thereof and spanning said opening and being joined together at their upper ends, said hinged doors normally resting on the hip rafters, means secured to the doors and extending downwardly to the lower portion of the barn for engagement by an operator for raising said doors.

GILDER S. HORNE.
